DRAFTING INSTRUMENT

Jessie T. Ivy, Seattle, Wash.

Application August 29, 1942, Serial No. 456,685

4 Claims. (Cl. 33—27)

My invention relates to the drawing or outlining of geometrical figures of predetermined contours, and has among its objects and advantages the provision of an improved drawing instrument for reproducing such figures in variable proportions.

In the accompanying drawings:

Figure 1 is a face view of the instrument;

Figure 2 is a side view;

Figure 3 is a top plan view with portions of 10 the supporting legs broken away;

Figure 4 is an enlarged sectional view along the line 4—4 of Figure 2;

Figure 5 is an enlarged sectional view along the line 5—5 of Figure 2;

Figure 6 is a sectional view along the line 6—6 of Figure 3;

Figure 7 is a sectional view along the line 7—7 of Figure 3;

Figure 8 is a cross sectional view of a pattern element which guides the instrument to draw a figure of predetermined contour;

Figure 9 is a sectional view of an inscribing rod;

Figure 10 is a fragmentary view of an extension for the inscribing rod;

Figure 11 is a fragmentary sectional view of a leg extension; and

Figure 12 is a sectional view of a diameter increasing sleeve insertable over the inscribing rod for coaction with the pattern element to reduce the size of the outline being inscribed;

In the embodiment selected for illustration, I make use of a head 10 to which is secured three supporting legs 12, 14 and 16. These legs are arranged in diverging relationship and each includes a threaded shank 18 threaded into a bore 20 in the bottom face of the head 10. Each leg is also provided with a fixation pin 22 at its lower end for engagement with the drawing surface 24 to support the instrument against accidental shifting.

Depending from the cradle 10 is an inscriber rod 26 comprising sections 28 and 30. Section 30 is provided with a threaded shank 32 threaded into a bore 34 in the section 28. To the lower end of the section 30 is connected a chuck 36 which carries the inscribing point 38 for engagement with the drawing surface 24. In Figure 9, the section 30 is provided with a bore 40 within which is mounted a compression spring 42, one end of the spring abutting the bottom wall of the bore and the other end abutting a flange 44 on the inner end of a small rod 46 to which the chuck 36 is connected. A

washer 48 is threaded into the lower end of the section 30 for slidably guiding the rod 46. In cases where a relatively long inscriber rod is required, particularly when outlining large patterns, an extension rod 50 is interposed in the inscribed rod 26. This extension rod includes a shank 52 threaded engageable in the bore 34 and a threaded bore 54 for connection with the shank 32.

The inscriber rod 26 is connected with the head 10 for universal movement. A ball 56 is formed at the upper end of the section 28, which ball is rotatably housed in a tapered neck 58 formed on one end of a sleeve 60 threaded into a bore 62 in the head 10.

Head 10 is provided with a vertical T slot 64 within which is slidably mounted a correspondingly shaped scale rule 66. The scale rule is supported at right angles to the drawing surface 24 and lies substantially in the plane of the supporting legs 12 and 14. Means for adjustably securing the scale rule 66 in selected operating positions comprises a screw 68 having a square head 70 lying in a correspondingly shaped recess 72 in the head 10. The recess 72 is deeper than the thickness of the head 10 and is so arranged as to bring the rear face of the scale rule 66 into engagement with the head 70, so that the scale rule may be fixedly secured through tightening of the nut 74.

To the lower end of the scale rule 66 is secured a cradle 76 within which is mounted a pattern element 78 in the nature of a washer. Figure 5 illustrates the pattern element 78 as being provided with a hexagonally-shaped opening 80 for the purpose of reproducing hexagonally contoured outlines. The inscriber rod 26 is located concentrically of the opening 80 when in the vertical position of Figure 2.

A shaft 82 extends through an opening 84 in the scale rule and is provided with a wedge-shaped key 86 receivable in a correspondingly shaped groove 88 in the peripheral face of the pattern element 78. A tapered point 90 is formed on the key 86 and extends into a correspondingly shaped recess 92 in the pattern element 78. A tapered recess 94 is formed on the peripheral face of the pattern element 78 diametrically opposite the recess 92 for the reception of the tapered end 96 of a screw 98. Thus the key 86 restrains the pattern element 78 from accidental rotation, while the screw 98 clamps the pattern element in a fixed position between the two pointed ends 90 and 96.

On the flat wall 100 of the cradle 76 is se-

cured a scale plate 102 also bored for the passing of the shaft 82. A pointer 104 is keyed to the shaft 82 and is held on the shaft against the plate 102 by a head 106 formed on a screw 108 threaded into the shaft 82. A knob 110 comprising a nut is mounted on a screw 112 extending through a slot 114 in the scale plate 102, which slot is concentrically arranged with respect to the axis of the shaft 82. The wall 100 is provided with a curved groove 116 for accommodating the head 118 on the screw 112. Thus the pointer 104 may be rotated about the axis of the shaft 82, and the scale plate 102 is provided with a scale 120 across which the end of the pointer 104 sweeps to indicate the various angular positions of the pattern element 78. The zero position of the scale is indicated at 122, so that the pattern element 78 will lie in a horizontal plane in parallelism with the drawing surface 24 when the pointer 104 registers with the zero position on the scale 120. Since the key 86 restrains the pattern element from rotation relatively to the shaft 82, rotation of the pointer 104 imparts corresponding rotation to the pattern element.

On the front face of the scale rule 86 is provided two scales 124 and 126 respectively associated with pointers 128 and 130 formed on the head 10.

In operation, a series of pattern elements 78 is employed, each pattern element having an opening of predetermined contour. In reproducing geometrical contours lying in a plane parallel to the drawing surface 24, the pointer 104 is moved to zero position and firmly latched by tightening the head or nut 110. When drawing the pattern, the instrument is held firmly by placing one hand on the head 10 and grasping the rod 46 and lifting the chuck end off the drawing surface. The inscriber rod 26 is then pivoted to a position at rest against the pattern element 78. The chuck end 36 is then brought into engagement with the drawing surface and the inscriber rod is moved in a path determined by the outline of the opening 80 for reproducing a correspondingly shaped figure on the drawing surface. The rod 46 is spring tensioned so that its chuck end 36 is held in proper pressure relationship with the drawing surface.

In reproducing pattern outlines lying in a predetermined angle to the horizontal, the pointer 104 is swung to the right or the left and to the desired degree mark on the scale 12, depending upon the direction of angle desired, after which the pointer is made secure and the inscriber rod 26 manipulated in the same manner as when outlining horizontal outlines. With a given set of pattern elements 78, each pattern may be reproduced in a large range of selected proportions, depending upon the vertical distance between the pattern element and the drawing surface 24. In outlining relatively small patterns, a sleeve 132 is slipped over the inscriber rod 26 to lie within the opening 80, thereby increasing the diameter of the inscriber rod 65 so as to produce a smaller outline.

In reproducing patterns of relatively large outline, each of the legs 12, 14 and 16 is provided with an extension 134, which extension is pro-

vided with a fixation point 136 and a threaded socket 138 for connection with the screw 140 at the lower end of the original leg. The extension rod 50 is interposed in the inscriber rod 26 when the leg extensions 134 are employed.

In addition to leg extension for varying the proportions of the pattern outlines, the scale rule 86 may be adjusted vertically to secure a multitude of proportional variations within the 10 respective ranges of the short and long legs. Scale 124 is employed for determining the proportions of the outlines when employing the short legs, while the scale 126 is employed when using the leg extensions. The sleeve 132 is employed only when reproducing pattern outlines less than one inch in diameter for maximum length. The leg 16 is provided with a pivoted pointer 142 which may be employed in certain types of drawing where it is desirable to locate 20 the instrument on a predetermined line located at right angles to a second predetermined line on which the fixation points of the legs 12 and 14 are located.

Without further elaboration, the foregoing will 25 so fully illustrate my invention, that others may, by applying current knowledge, readily adapt the same for use under various conditions of service.

I claim:

1. A drafting instrument comprising a head 30 having supporting legs, an inscribing rod depending from said head, a universal connection between the upper end of the inscribing rod and said head, a pattern contour guide located to engage the inscribing rod intermediate its ends to control its inscribing movement, extensions for said legs, and means for varying the size of the inscribing rod at its point of engagement with the pattern contour guide to vary the size of the pattern reproduced by the inscribing rod.

2. A drafting instrument comprising a head 40 having supporting legs, an inscribing rod having a universal connection with said head, a pattern contour guide located to engage the inscribing rod intermediate its ends to control its inscribing movement, a cradle fixedly related to said head, and pivot means on said cradle supporting said 45 pattern contour guide for pivotal movement about a horizontal axis.

3. A drafting instrument comprising a head 50 having supporting legs, an inscribing rod having a universal connection with said head, a pattern contour guide located to engage the inscribing rod intermediate its ends to control its inscribing movement, a ruler member slidably mounted on said head for vertical movement, a cradle attached to said ruler member, and first 55 and second pivot means carried by said cradle for supporting said pattern contour guide for movement about a horizontal axis, said first pivot means being threadedly connected with said cradle and adjustable for loosely or fixedly supporting the pattern contour guide.

4. The invention described in claim 3 wherein 60 said cradle is provided with a scale, and a pointer attached to said second pivot means coacting with said scale to denote the angular position of said pattern contour guide.

JESSIE T. IVY.
